Filed Nov. 27, 1972, Ser. No. 309,907

Term of patent 14 years

Int. Cl. D23—04

U.S. Cl. D23—149

FIG. 1 is a perspective view of a mobile device for directing filtered air onto a bed or the like showing my new design;

FIG. 2 is a front elevational view thereof on a reduced scale;

FIG. 3 is a side elevational view thereof on a reduced scale;

FIG. 4 is a perspective view of the mobile device in a collapsed condition on a reduced scale;

FIG. 5 is a perspective view of the mobile device in the collapsed condition of FIG. 4 but resting on its rear wall.

The underside of the hinged member adjacent the rectangular housing is substantially plain and unornamented.

I claim:

The ornamental design for a mobile device for directing filtered air onto a bed or the like, substantially as shown and described.
